(57) **CLAIM**

I claim the ornamental design for the multi-angle incline dumbbell bench press, as shown and described.

DESCRIPTION

FIG. 1 is a front elevational view of the multi-angle incline dumbbell bench press showing my new design;
FIG. 2 is a rear elevational view thereof;
FIG. 3 is a right side elevational view thereof;
FIG. 4 is a top plan view thereof;
FIG. 5 is a bottom plan view thereof;
FIG. 6 is a front perspective view thereof; and,
FIG. 7 is a rear perspective view thereof.
